UNITED STATES PATENT OFFICE.

LESLIE H. BURLIN, OF CHICAGO, ILLINOIS.

DESIGN FOR A PEDESTAL OR SIMILAR ARTICLE.

Application filed June 19, 1924. Serial No. 9,917. Term of patent 14 years.

To all whom it may concern:

Be it known that I, LESLIE H. BURLIN, a citizen of the United States of America, residing at Chicago, in the county of Cook and State of Illinois, have invented a new, original, and ornamental Design for a Pedestal or Similar Article, of which the following is a specification, reference being had to the accompanying drawing, forming a part thereof, and in which—

Figure 1 is a perspective view and Fig. 2, a top plan of a base for a pedestal or similar article, showing my new design.

My base for a pedestal or similar article is made and sold as a complete and separate similar article, as shown.

I claim:

The ornamental design for a pedestal or similar articles, as shown.

LESLIE H. BURLIN.
